UNITED STATES PATENT OFFICE.

THOMAS EDWIN KIRK, OF COLUMBUS, OHIO, ASSIGNEE OF ONE-HALF TO JOHN GEORGE
KIRK, OF COLUMBUS, OHIO.

WINDOW-CLEANING DEVICE.

1,152,519.

Specification of Letters Patent.

Patented Sept. 7, 1915.

Application filed July 14, 1914. Serial No. 650,052.

To all whom it may concern:

Be it known that I, THOMAS E. KIRK, a citizen of the United States, residing at Columbus, in the county of Franklin and State of Ohio, have invented a new and useful 5 Window-Cleaning Device, of which the following is a specification.

The invention relates to improvements in window cleaning devices. 10 The object of the present invention is to improve the construction of window cleaning devices and to provide a simple, practical, and efficient device of strong and durable construction, designed for use on various kinds of cars, locomotives, vessels, automobiles, and other conveyances having exposed glass windows or doors, as well as on display windows and the like, and capable of being easily and quickly operated from 15 the interior while such vehicle is in motion to wipe rain, snow, sleet, etc., from a window in a door or wall, to prevent such accumulation on the exterior of the window from obstructing the view.

With these and other objects in view the invention consists in the construction and novel combination of parts hereinafter fully described, illustrated in the accompanying drawings, and pointed out in the claims. 20 Hereto appended, it being understood that various changes in the form, proportion, size and minor details of construction, within the scope of the claims, may be resorted to without departing from the spirit or sacrificing any of the advantages of the invention.

In the drawings: Figure 1 is a perspective view of a cleaning device constructed in accordance with this invention, and shown 25 applied to a window. Fig. 2 is a perspective view of one side of the window, showing the operating device. Fig. 3 is a transverse sectional view. Fig. 4 is a vertical sectional view on the line 4-4 of Fig. 3. Fig. 5 is a similar view taken substantially on the line 5-5 of Fig. 3. Fig. 6 is a vertical sectional view taken substantially on the line 6-6 of Fig. 3. Fig. 7 is a detail perspective view of one end of the wiper. Fig. 8 is a detail sectional view showing the 30 loop shaped arms and the connecting links. Fig. 9 is a detail perspective view of the outer portion of one of the exterior casings. Fig. 10 is a detail vertical sectional view 35 illustrating the position of the upper and

lower arms of the pivots when the wiper is moving upwardly and is out of engagement with the glass of the windows.

Like numerals of reference designate corresponding parts in all the figures of the drawings.

In the accompanying drawings, in which is illustrated the preferred embodiment of the invention, 1 designates a wiper extending across the exterior of a window 2 and 40 movable upwardly and downwardly over the same and adapted, in its downward movement, to contact with and wipe the outer face of the glass to remove therefrom rain, snow, sleet, and other accumulation, so as to 45 prevent the same from interfering with the view from the interior. The cleaning device is designed for use on various kinds of exposed windows, and the wiper 1, which may be of any preferred construction, is illustrated in the accompanying drawings as consisting of a metallic body portion 3 and a flexible engaging or wiping portion 4, consisting of a strip of soft rubber or other material. The metallic body portion 50 consists of a strip of sheet metal folded longitudinally to provide two sides and a connecting portion, which is in the form of a bead 5 to receive a transverse shaft or rod 6. The sides 3 of the sheet metal body portion 55 receive and clamp between them the strip 4, which is also folded longitudinally to provide two plies or thicknesses, as clearly shown in Fig. 7 of the drawings. The reinforcing or stiffening rod 7 is arranged in 60 the fold of the flexible strip 4, and the sides of the body portion 3 are slightly bowed to 65 conform to the configuration of the folded reinforced portion of the strip 4.

The transverse shaft or rod 6, which projects beyond the ends of the wiper, constitutes a pivot for the same, and its projecting terminal portions are slidable along spaced guide rails 8 located at opposite sides of the window and extending along the same 70 from the top to the bottom thereof. The wiper, which is arranged at an inclination, extends upwardly and inwardly from the shaft or rod 6, and it is equipped at its terminals with laterally projecting studs or 75 portions 9 arranged in spaced relation with the projecting terminal portions of the shaft or rod and slidable along the inner faces of the guide rails 8 in the downward movement of the wiper and along the outer faces 80

of the guide rails 8 in the upward movement of the wiper, to maintain the wiper in engagement with the glass of the window during the said downward movement and to 5 carry the engaging portion of the wiper away from the glass while the wiper is traveling upwardly to return it to the top of the window. The guide rails, which are carried by inner sections 10 of side casings, 10 may consist mainly of laterally projecting vertically disposed flanges of the said sections 10, and they are provided with upper portions 11 outwardly offset by bends 12 and adapted, after the wiper has reached the 15 limit of its inward movement, to receive the projecting studs 9 and guide the same to the inner faces of the vertical guide rails 8. The guide rails are provided at their lower ends with inwardly curved resilient portions 13 set at a slight inclination and adapted 20 to be deflected by the studs 9 in the downward movement of the wiper, and after the said studs 9 have been carried downwardly past the said resilient portions, the said resilient 25 portions spring inwardly beyond the said studs, which are caused to ride upwardly over the outer faces of the said guide rails. The guide rails, by the particular construction of their upper and lower portions, automatically 30 guide the wiper in the upward and downward movements thereof. By arranging the wiper out of engagement with the glass during its upward movement, the wiper is relieved of friction and requires 35 but little effort to return it to its elevated position.

The terminal projecting portions of the pivot 6 carry upper and lower arms 14 and 15 arranged in pairs and disposed at an inclination. These arms, which consist of loops, may be formed of a continuous strip of metal, as clearly illustrated in Figs. 7 and 8 of the drawings, but they may be made in any other desired manner, and the lower 40 arm 15 is of greater length than the upper arm 14. The openings 16 and 17 of the arms 14 and 15 receive antifriction rollers 18 and 19 of upper and lower links 20 and 21, which connect the arms with upper and 45 lower metallic tapes or strips 22 and 23. The links 20 and 21, which are rectangular, are composed of spaced sides and transverse connecting portions, the outer transverse connecting portions being secured to the adjacent 50 ends of the tapes and the inner transverse connecting portions being arranged within the openings 16 and 17 of the arms 14 and 15, and having the said antifriction rollers 18 and 19 mounted on them. The 55 rollers enable the links to move frictionlessly in the openings 16 and 17 of the upper and lower arms 14 and 15 during the pivotal movement of the wiper, which is tiltable on its pivot to carry it to and from the positions illustrated in Figs. 4 and 10 of the

drawings. When the wiper is in the position illustrated in Fig. 4 of the drawings, the arms extend downwardly from the pivot 6, and the upper roller is arranged at the inner end of the upper arm 14, while the 70 lower roller is located at the outer end of the lower arm 15, as clearly illustrated in Fig. 8 of the drawings. In the upward movement of the wiper, when the latter is reversed and occupies the position illustrated in Fig. 10 of the drawings, the arms 14 and 15 extend upwardly from the pivot 6. In this position the upper roller is arranged in the outer end of the upper arm, having moved from one end to the other 75 end thereof. The lower roller 19 is also located at the inner end of the lower arm, having moved inwardly from the outer end thereof through the tilting of the wiper. When the wiper is arranged as shown in Fig. 4, the long lower arm affords considerable leverage for pressing the wiper against the glass when the lower flexible tapes or strips are pulled downwardly. 85

The flexible tapes or strips may be constructed of any suitable material, and the upper strips or tapes are connected with and wound around upper pulleys 24 of a hollow spring actuated roller 25 mounted in bearing brackets 26 and 27 and containing a coiled spring 28 connected at one end with the roller and at the other end with a relatively fixed journal 29. The relatively fixed journal 29, which consists of a rod, has a squared portion 30 to receive a key or wrench, and it is equipped with a ratchet wheel 31. The ratchet wheel 31 is engaged by a pawl 32 pivotally mounted on the bracket 27 and maintained in engagement with the ratchet wheel by a spring 33. The relatively fixed journal rod 29 is adapted to be rotated to wind up the spring for placing the same under the desired tension. When the wiper is moved downwardly by means hereinafter described, the upper flexible strips or tapes are unwound from the pulleys 24 of the spring actuated roller 25, and the tension of the spring 28 is thereby increased, so that the said spring will operate to raise the wiper when the latter is released by the operator. The lower flexible strips or tapes 23 are wound around pulleys 34 of a hollow shaft 35, journaled in lower bearing brackets 36 and carrying a pulley 37 around which is wound an operating tape or strip 38. The pulleys 24, 34, and 37 are flanged to prevent lateral displacement of the flexible strips or tapes, and the operating tape 38 extends inwardly from the pulley 37 through an opening 39 to the inner side of the window, and is connected with a vertically movable slide or operating member 40. The flexible operating connection 38 is guided by upper and lower pulleys 41 and 42, and it extends upwardly from the lower pulley 42 to the 90 95 100 105 110 115 120 125

upper pulley 41 and passes over the top of the latter and downwardly therefrom to the operating slide or member 40. The operating slide or member 40, which is provided at its sides with grooves 43, is mounted in a guide 44 consisting of a sheet metal casing composed of spaced sides and a connecting front portion. The guide 44, which is arranged in a vertical position at one side of the window, is provided at opposite sides with attaching flanges 45, and it has a longitudinal slot 46 in its front portion. The operating slide or member 40 is arranged in the slot and its side grooves are engaged by the edges of the front portion of the casing 44 at the sides of the said slot. The operating slide or member is equipped with a handle 47 preferably curved as shown to fit the finger and adapted to be drawn downwardly to unwind the operating tape or connection from the pulley 37. The operating tape or strip 38 is wound around the pulley 37 in a direction opposite to that in which the lower tapes or flexible connections are wound, so that when the lower roller is rotated by the unwinding of the flexible strip or tape 38, the lower flexible strips or tapes will be wound around the lower pulleys 34, and will move the wiper downwardly. This operation also unwinds the upper tapes or strips from the upper spring actuated roller, which returns the wiper to its elevated position at the top of the window.

The guide pulleys 41 and 42 are mounted in the upper and lower portions of the guide or casing 44 and are carried by the same. The inner sections 10 of the side exterior casings consist of strips of sheet metal provided with longitudinally disposed right angle bends forming inner or rear walls, inner side flanges 48, and the said guide rails 49. The exterior side casing is composed of the said inner section 10 and outer sections or caps 49, also constructed of sheet metal and provided with longitudinally disposed right angle bends which form an outer side wall, front walls, and flanges 50 and 51. The flanges 50 are secured to the inner walls or portions of the inner sections 10 and the flanges 51 are arranged in the same planes as the flanges 48, and are spaced from the guide rails and the flanges 48 to provide openings having straight walls and forming straight longitudinal guides or ways for the projecting terminals of the pivot rod 6 of the wiper. The removable caps or outer sections permit convenient access to the interior of the side casing, but the latter may, of course, be constructed in any other desired manner.

The window is equipped at the bottom with a fixed scraper 52, constructed of sheet metal or other suitable material and extending upwardly and outwardly at the bottom of the window in the path of the engaging

or wiping portion of the wiper, so as to scrape snow, sleet, or other accumulation therefrom when the wiper reaches the bottom of the window. The scraper 52, which has an attaching portion 53, is also provided with a longitudinal slot or opening 54, located below the engaging edge or portion of the scraper and adapted to permit the snow, sleet, or other accumulation removed by the scraper to fall through the latter, whereby the snow, sleet, or other accumulation scraped from the window is prevented from accumulating at the bottom thereof.

The wiper is limited in its upward and downward movements by upper and lower stops 55 and 56, which may consist of projecting points, as shown in the accompanying drawings, but any other suitable means may, of course, be employed for limiting the upward and downward movements of the wiper.

What is claimed is:

1. A cleaning device of the class described including straight spaced guides or ways, spaced guide rails located at the guides or ways, and a wiper having terminal pivots 100 slideable in the guides or ways, said wiper being also provided with projecting means slideable along the guide rails and arranged at the inner faces of the same during one of the movements of the wiper and at the outer faces of the said guide rails during the other movement of the wiper, said guide rails being provided with terminal portions for automatically guiding the said projecting means to the other face of the rails.

2. A cleaning device of the class described including straight spaced guides or ways, spaced guide rails located at the guides or ways, and a wiper having terminal pivots 105 slideable in the guides or ways, said wiper being also provided with projecting means slideable along the guide rails and arranged at the inner faces of the same during one of the movements of the wiper and at the outer faces of the guide rails during the other movement of the wiper, said guide rails being provided with terminal offset portions arranged to guide the said projecting means to the other face of the rails.

3. A cleaning device of the class described including spaced guide rails to be mounted at opposite sides of a window, and a wiper slideable along the guide rails and having projecting means arranged at the inner 110 faces of the guide rails during one of the movements of the wiper, and at the outer faces of the guide rails during the other movement of the wiper, said guide rails being provided at one end with fixed offset 115 portions and having yieldable portions at the other end arranged to be flexed by the said projecting means.

4. A cleaning device of the class described including spaced casings provided with 120

straight longitudinal slots, guide rails located at the said slots, and a wiper having pivots slidable in the slots, said wiper being also provided with separate projecting means slidable along the guide rails, and means for actuating the wiper.

5. A cleaning device of the class described including spaced guide rails, a wiper slideable along the same and tilttable to move it 10 into and out of contact with a window, said wiper being provided with arms having openings, links slidable in the openings to facilitate such tilting movement of the wiper, and means connected with the links for moving 15 the wiper along the guide rails.

6. A cleaning device of the class described having spaced guide rails, a wiper slideable along the same and having a pivot and tilttable thereon to move it into and out of contact with a window, said wiper being also provided with arms located above and below the said pivot and having openings, links movable in the openings to facilitate the said 25 tilting movement of the wiper, and means connected with the links for moving the wiper upwardly and downwardly along the guide rails.

7. A cleaning device of the class described including spaced guide rails, a wiper slideable along the same and tilttable to move it into and out of contact with a window, said wiper being provided with upper and lower arms arranged at an inclination, the lower arms being longer than the upper arms, 35 and means slidably connected with the arms for moving the wiper upwardly and downwardly along the guide rails.

8. A cleaning device of the class described including spaced guide rails, a wiper slideable along the same and tilttable to move it into and out of contact with a window, said wiper being provided at its ends with upper and lower arms arranged at an inclination and having openings, links having antifriction devices slidable in the openings of the said arms to facilitate such tilting movement of the wiper, and means connected with the links for moving the wiper upwardly and downwardly along the guide rails.

50 9. A cleaning device of the class described including guide rails to be mounted at opposite sides of a window, a wiper having projecting pivots slidable along the guide rails, studs spaced from the pivot and also 55 movable along the inner and outer faces of the guide rails to hold the wiper in contact with the window in one movement of the wiper along the guide rails, and to maintain the wiper out of such contact during its other movement along the said rails, and means connected with the wiper for actuating the same.

10. A cleaning device of the class described including spaced guiding means to be located at opposite sides of a window ex-

teriorly thereof, a wiper slideable along the said guiding means, upper and lower rollers having pulleys, flexible connections wound around the pulleys and connected with the wiper for moving the same upwardly and 70 downwardly, a slideable operating member arranged at the inner side of the said window, a flexible connection extending from the slideable member, a pulley receiving such flexible connection and mounted on one of 75 the said rollers, and a spring connected with the other roller.

11. A cleaning device of the class described including spaced guiding means to be mounted on a window exteriorly thereof, 80 a wiper movable along the said guiding means, upper and lower rollers provided with pulleys, flexible connections wound around the pulleys and connected with the wiper, a guide mounted at the inner side of 85 the window, a slideable member movable along the said guide and provided with operating means, a flexible connection extending from the slideable member to the lower roller and arranged to rotate the same 90 to move the wiper in one direction, and a spring connected with the upper roller for moving the wiper in the opposite direction.

12. A cleaning device of the class described including spaced guiding means to be mounted on a window exteriorly thereof, 95 a wiper movable along the said guiding means, upper and lower rollers provided with pulleys, flexible connections wound around the pulleys and connected with the 100 wiper, a hollow guide mounted at the inside of the window and provided with a longitudinal slot, a grooved slide interlocked with the guide at the said slot, pulleys mounted within the guide, a flexible connection arranged on the pulleys of the said guide and connected at one end with the slideable member and at the other end with the lower roller for moving the wiper in one direction, 105 and a spring connected with the upper roller 110 for moving the wiper in the opposite direction.

13. A cleaning device of the class described including a wiper, means for moving the same upwardly and downwardly over a 115 window, and a fixed scraper arranged in the path of the wiper for removing accumulation therefrom.

14. A cleaning device of the class described including a wiper, means for moving the same upwardly and downwardly over a 120 window, and a fixed scraper arranged in the path of the wiper for removing accumulation 125 therefrom, said scraper being provided with an opening to permit the accumulation scraped from the wiper to fall through the scraper.

15. A cleaning device of the class described including a wiper, means for moving the same upwardly and downwardly over a 130

window, and a fixed scraper having means for mounting it on a window at the lower portion thereof in the path of the wiper and set at an angle or inclination.

5 16. A cleaning device of the class described including a wiper movable upwardly and downwardly, means for tilting the wiper to carry it into and out of contact with a window, said wiper being provided
10 with inclined arms having openings, and means for moving the wiper upwardly and downwardly including links movable in the

openings from one end to the other thereof through the tilting of the wiper, said links being adapted to hold the wiper in and out 15 of contact with the window.

In testimony, that I claim the foregoing as my own, I have hereto affixed my signature in the presence of two witnesses.

THOMAS EDWIN KIRK.
